[57] CLAIM

The ornamental design for a package dispenser, as shown and described.

DESCRIPTION

FIG. 1 is a perspective view of a package dispenser showing out new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view of FIG. 3;

FIG. 7 is a bottom plan view FIG. 3;

FIG. 8 is a top plan view thereof shown in an unfolded condition;

FIG. 9 is a front elevational view of a second embodiment of FIG. 1;

FIG. 10 is a right side elevational view of FIG. 9;

FIG. 11 is a rear elevational view of FIG. 9;

FIG. 12 is a left side elevational view of FIG. 9;

FIG. 13 is a top plan view of FIG. 10; and,

FIG. 14 is a bottom plan view of FIG. 10.

FIGS. 2-7 and 9-14 are shown in reduced scale in comparison to FIGS. 1 and 8. The broken lines represent perforations defining removable tabs and tear strips and break lines.
